(57) **CLAIM**

The ornamental design for a puzzle container, as shown and described.

DESCRIPTION

FIG. 1 is a front perspective view of a puzzle container showing the new design;

FIG. 2 is a front view thereof;

FIG. 3 is a back view thereof;

FIG. 4 is a top view thereof;

FIG. 5 is a bottom view thereof;

FIG. 6 is a left side view thereof;

FIG. 7 is a right side view thereof; and,

FIG. 8 is a top perspective view thereof of the design in the context in which it is intended to be used, the dashed lines form no part of the claimed design.
